(57) CLAIM

The ornamental design for a base for containers and holders, as shown and described.

DESCRIPTION

FIG. 1 is a perspective view of the base for containers and holders according to the invention;

FIG. 2 is a top view of the base for containers and holders as shown in FIG. 1;

FIG. 3 is a side view of the base for containers and holders as shown in FIG. 1; and,

FIG. 4 is a bottom view of the base for containers and holders as shown in FIG. 1.
